E. R. LE MANQUAIS.
WALL CABINET FOR ELECTRICAL APPARATUS.
APPLICATION FILED MAY 11, 1907.

942,002.

Patented Nov. 30, 1909.

UNITED STATES PATENT OFFICE.

ERNEST R. LE MANQUAIS, OF BELLEMEAD, NEW JERSEY, ASSIGNOR TO LE MANQUAIS ELECTRICAL MANUFACTURING COMPANY, OF BELLEMEAD, NEW JERSEY, A CORPORATION OF NEW JERSEY.

WALL-CABINET FOR ELECTRICAL APPARATUS.

942,002.

Specification of Letters Patent. Patented Nov. 30, 1909.

Application filed May 11, 1907. Serial No. 373,123.

To all whom it may concern:

Be it known that I, ERNEST R. LE MANQUAIS, a citizen of the United States, residing in Bellemead, New Jersey, have invented certain Improvements in Wall-Cabinets for Electrical Apparatus, of which the following is a specification.

One object of my invention is to provide an inclosing structure for the reception of electrical apparatus and having its parts so arranged as to permit of a number of current conductors being conveniently brought into it and attached to the apparatus with a minimum expenditure of time and labor.

Another object of the invention is to provide an inclosing box primarily designed for insertion into an opening or recess in a wall and having its side members made in a plurality of separable parts in order to permit 20 of the removal of one or more of such parts when it is desired to remove or replace a bushing or bushings mounted in openings along the lines of separation of the parts comprising each side.

Another object of the invention is to provide a container or cabinet constructed with its side members made each in two separable parts and having each part recessed along its line of separation to receive bushings designed either to completely close such recesses or to form insulating supports or carriers for a cable passing through them.

I further desire to provide a cabinet for the reception of electrical apparatus, with 35 novel forms of bushings for protecting electrical conductors where they enter said cabinet.

These and other advantageous ends I attain as hereinafter set forth, reference being had to the accompanying drawings, in which:

Figure 1, is a perspective view of my improved wall cabinet; Fig. 2, is a horizontal section of the cabinet shown in Fig. 1, illustrating certain details of its construction. Fig. 3, is a horizontal section similar to Fig. 2, and illustrating the separable side members of the device as moved into position to release the bushings held between them. Fig. 4, is a perspective view on an enlarged scale illustrating a detail of the invention, and Figs. 5 to 10 inclusive are perspective views of various forms of bushings which

may be employed in connection with my improved cabinet.

55

In the above drawings A represents the face plate of the cabinet which is provided with an opening capable of being closed by a door B, hinged in any desired manner to said face plate.

60

The box or container proper as indicated at C, consists of end sections c and c' having between them any desired number of intermediate sections c², in the present instance, one.

65

Each end section is provided with a back c³, an end c⁴ and two side portions c⁵; while each intermediate portion has a back c⁶ and two sides c⁷. The end c⁴ of each of the end sections c and c', has a removable section b 70 which, as shown in Figs. 2, 3 and 4, is confined between the face plate and the main portion of the sections, and is provided with flanges b' and b², whereby it is properly positioned on the said body. In addition, 75 each of these parts b is provided with projecting lugs b³ having screws b⁴ whereby the said part is held to adjacent portions of the body of the end section. Similarly, the side portions of each end section, as well as 80 the side portions of the intermediate section c⁶, are recessed to receive removable plates b⁵ similar to plate b. Like it, plate b⁵ is provided with positioning flanges and also has lugs b³ whereby it is held in position between the various portions c, c' and 85 c² and the face plate.

90

The inner main edge of each of the removable plates b and b⁵ is provided with a number of semicircular recesses of any desired dimensions, and the adjacent edge of the end sections or of the side sections as the case may be, is similarly recessed, so that there are formed, when the various parts are assembled, a number of circular openings 95 through the sides and ends of the box. It will be understood that the various sections of this box are held together and to the face plate in any desired manner, though preferably as shown in the patent granted to me 100 No. 782,255, dated Feb. 14, 1905.

Each of the circular openings is in practice preferably provided with a bushing D as shown in Fig. 6, if it be desired that it shall be completely closed, or on the other hand, if it be desired to provide means for

105

the entry of current conductors, a bushing such as that shown at D in Fig. 5, may be provided.

In a case where it is desired to run two or 5 more conductors through one hole in the cabinet and to keep these out of contact with each other to as great an extent as possible, I may employ the forms of bushing shown in Figs. 7 and 8. In these figures D² and 10 D³ represent bushings designed for the passage of two and three conductors respectively and both their inner and outer faces are provided with partitions d² and d³ projecting for any desired distance between the 15 openings for the conductors.

In order to permit of the convenient placing of electrical conductors in the bushings, these latter may be made in two longitudinally divided sections as shown at D⁴ in 20 Figs. 9 and 10, in which the two sections d⁴ and d⁵ are provided with lugs for the reception of screws whereby they may be clamped to the armor or insulation of the conductors. This construction is further shown in Fig. 10 25 where E represents a piece of the armor or metallic covering of a well known form of electrical conductor and which is clamped between the two suitably formed sections of the bushing. If desired the bushing may be 30 given any convenient form in order to direct a conductor at an angle other than 90° to the adjacent face of the cabinet. Thus in Fig. 10 I have shown the bushing so formed as to receive a cable running at an angle of 35 45° to the cabinet face. In any case the bushing is flanged on both faces so as to be retained in position in one of the circular openings as long as the removable plate b or b⁵ remains in place. In order to remove the 40 bushing, or to replace one form of bushing by another, it is only necessary to remove the face plate A when, after the screws b⁴ have been taken out, the removable plate or portion b or b⁵ may be moved out as shown in 45 Fig. 3 so as to release the bushings.

I usually construct the bushing D of two stamped pieces of sheet metal held together by a rivet d, while the bushings D' are usually of insulating material and provided 50 with one or more holes d' for the passage of current conductors.

It is of course obvious that if desirable, current conductors may be run directly through the circular openings in the sides

and ends of the box without being provided 55 with bushings although it is usually preferable to employ these latter.

I claim as my invention:

1. A box having a side portion partly formed of a plurality of independently removable sections, a plate shaped to co-act with said sections to complete said side portion, the adjacent edges of the removable sections and of said plate being respectively provided with a recess or recesses, each recess of the plate registering with a recess of one of the sections to form an opening, and a flanged bushing or bushings mounted in said recess or recesses. 60

2. The combination of a box having a removable face plate, with a removable section formed to complete one of the sides of the box and confined between the body thereof and said face plate, said section being independent of the face plate and of the other 75 sides of the box, and the adjacent edges of the section and of the body of the box being respectively provided with registering recesses to provide an opening or openings. 70

3. A box consisting of two end sections 80 and an intermediate section between the same, the side portions of said sections being cut away and each of said cut away portions being replaced by a removable plate, there being a recess or recesses formed in the adjacent edges of said plate and said side portions, each recess of the plate registering with a recess on the side portion substantially as described. 85

4. A box consisting of two end sections 90 and an intermediate section between the same, the side portions of said sections being cut away and each of said cut away portions being replaced by a removable plate, there being a recess or recesses formed in the adjacent edges of the said plate and said side portion, each recess of the plate registering with a recess of the side portion with a face plate for the box and a flanged bushing in each of the openings formed by the said recesses, substantially as described. 95

In testimony whereof, I have signed my name to this specification, in the presence of two subscribing witnesses.

ERNEST R. LE MANQUAIS.

Witnesses:

W.M. A. BARR,

ROBERT A. KAISER.
